UNITED STATES PATENT OFFICE.

LOUIS P. LIPPS, OF CLEVELAND, OHIO, ASSIGNOR TO LOUIS P. LIPPS, TRUSTEE, OF ONE-HALF FOR HIMSELF, ONE-FOURTH FOR WILLIS L. WESTCOTT, AND ONE-FOURTH FOR GEORGE C. WING, ALL OF CLEVELAND, OHIO.

METHOD OF ARRANGING TICKETS FOR STREET-CARS.

1,017,007.

Specification of Letters Patent. Patented Feb. 13, 1912.

Application filed April 10, 1911. Serial No. 620,180.

To all whom it may concern:

Be it known that I, LOUIS P. LIPPS, a citizen of the United States, residing at Cleveland, in the county of Cuyahoga and State of Ohio, have invented a new and useful Method of Arranging Tickets for Street-Cars and Similar Purposes, as to which I hereby declare the following to be a full, clear, and exact description, reference being had to the drawings that accompany and make a part of the specification, in which drawings the same parts are designated by the same letters throughout the several figures.

The invention relates to and is more particularly concerned with the class of tickets of the kind in question which are issued and sold in sets or series connected together in a single piece or strip from which the individual members of the series may be separately detached as occasion demands. So far as I know the only manner of making up a series of this sort that has heretofore been proposed is by printing the requisite number of tickets on successive and uniform rectangular portions of a blank of cardboard, or similar foldable material, with transverse scores or perforated lines of separation between the same along which the tickets may be folded, one against the other, into a compact form for carrying, and be severally torn away as required for use. The packet thus made up is of course of the precise superficial dimensions of the respective members thereof, with each ticket exactly corresponding or registering, in respect to its relative location, with every other ticket in the set, and without any tangible distinction between the same. It results that the tickets to be used are not readily selected and separated from the rest, and in consequence, in pay-enter cars, for instance, the entrance of other passengers is often held back while a ticket is being disconnected and deposited, and in all cases there is a liability that a passenger will tear off and surrender a greater number of fares than is intended.

I further set out herein a special arrangement of tickets for the purposes under consideration that is intended to meet the requirements or conditions of the systems of transfers that prevail in many cities. In these systems, the privilege of changing over

to and finishing their ride on a connecting line, is given to passengers who have paid one fare upon the payment by them of a small extra charge, of one cent, or more. Upon the surrender of the main ticket and the payment of this extra charge, the conductor punches and issues a transfer slip or ticket to the passenger, as the evidence of his right to transfer to another car, which must be specially given up to and received by the conductor on the car to which transfer is made. This system, as practiced, may involve, in the operations of a single company, the separate collecting and handling by conductors of many millions of the minor coin-pieces annually, with a corresponding amount of petty details on the part of other employees that it is desirable to avoid, while the inevitable incidents of its enforcement are a frequent source of annoyance to the traveling public, and of constant delays in the scheduled running of the cars and operations connected therewith.

In the drawings Figure 1 represents a series of six blank tickets arranged according to one method covered by the invention, and, Fig. 2 the same series when doubled back upon themselves for convenience of carrying. Fig. 3 is a like series when made according to another rule, and Fig. 4, the same series when similarly folded up, and Fig. 5 is a set of tickets adapted for the transfer systems referred to.

In Fig. 1 rectangular tickets *a*, *a*, *a*, are arranged through the series alternately with similar tickets *b*, *b*, *b*. The latter, however, are slightly wider than the former with the result that, when the tickets composing the series are bent over against each other along the dotted lines in the figures, the folds thus formed will alternately overlap and underlap the next adjacent fold in a succession of step-like projections along the opposite sides of the packets, on the front and rear face of the same, that afford a means by which the packet can be readily opened out, and the tickets disconnected in the regular order in which they occur. A like succession of projections may be brought about at the ends of a packet, (instead of at the sides) by folding the tickets obliquely across the sheet upon the dotted lines shown in Fig. 3. In this case the blank composing the tickets is rhomboidal in form, being a parallelogram

with oblique angles, wherein the adjoining sides are unequal.

The device illustrated by Fig. 5, consists of a rectangular sheet divided into equal ticket spaces by transverse scores or perforations, indicated in the drawings by the dotted lines. These spaces are themselves cut by a similar score or line that extends at right angles to the same at a uniform distance from the side of the sheet. The sheet is thus divided up into a series (in this case) of six oblong detachable tickets *d*, which may serve for the initial or main fare, and a smaller detachable ticket or coupon *e*, at the end of each ticket *d*, to serve in the place of the cent, or other coin, that now must be handed in as the price of a transfer. When the face value or denomination of the ticket proper is divisible by that of the coupon, it is evident that, by making the number of tickets in a given set a common multiple of these values, the coupons may be broken up into and used as principal tickets and without leaving odd coupons of less value than the main fare upon the sheet. Tickets, with transfer coupons made up in sheets in this manner may thus be the only form in which tickets are issued, and may be sold to passengers indifferently without regard to whether they are to be used in connection with transfers or only for uninterrupted rides. If the denomination or unit value of the principal ticket is three cents, for instance, and of the transfer one cent, as in Fig. 5, the card or sheet should then contain either three main tickets, and corresponding coupons, or six, nine, etc. If such values are respectively four and two cents, the set should be made up of two, four or six tickets, and, so on in similar cases. The adoption of the plan disclosed in Fig. 5, will accordingly reduce the transactions connected with the privilege of street-car transfers to a minimum, and

merge the same, for the most part, in the purchase of the principal tickets to which such right is incident. Obviously, the coupons *e* may be given adequate dimensions to be punched or stamped to take the place of and answer as the transfer-slips themselves, which will of course, further simplify the process of transference as now practiced. So too, the same arrangement may be conveniently used in connections where differences in accommodations or conditions are to be reconciled by a difference in fares, as where first and second-class cars are used in the same train, different grades of compartments or seats in the same car, or, when the quality of service afforded passengers in the same car materially varies in other respects.

Manifestly, the several methods of folding hereinbefore pointed out and illustrated for sheets of ordinary tickets, can be applied to and adopted, with equal advantage, for sheets to which coupons are attached as just explained.

Having thus described my invention, what I claim as new and desire to secure by Letters Patent is:—

1. As an article of manufacture, a series of tickets for street-cars, detachably connected together along their sides, and having alternate members of the series of different width from the rest, substantially as shown and described. 75

2. As an article of manufacture, a rectangular sheet of tickets for street-cars, with weakened folding lines across the same between the tickets at alternately different intervals, substantially as shown and described. 80

LOUIS P. LIPPS.
